(57) **CLAIM**

The ornamental design for a lawn mower blade balancer, as shown and described.

DESCRIPTION

FIG. 1 is a first perspective view thereof;
FIG. 2 is a second perspective view thereof;
FIG. 3 is a third perspective view thereof;
FIG. 4 is a front view thereof;
FIG. 5 is a rear view thereof;
FIG. 6 is a left side view thereof;
FIG. 7 is a right side view thereof;
FIG. 8 is a top view thereof; and,
FIG. 9 is a bottom view thereof.

The broken lines in the drawings illustrate the portions of the lawn mower blade balancer, which form no part of the claimed design.

1 Claim, 9 Drawing Sheets
